METHOD OF MAKING DECORATIVE SHEETS

Samuel H. Hartman, Lancaster Township, Lancaster County, Pa., assignor to Armstrong Cork Company, Lancaster, Pa., a corporation of Pennsylvania

Application August 1, 1939, Serial No. 287,699

7 Claims. (Cl. 18—61)

This invention relates to a method of manufacturing decorative sheets suitable for use as floor or wall coverings and, more particularly, to a method of making linoleum having a variegated surface effect, the word "linoleum" being used as a word of general definition and not of limitation, it being intended to include other or equivalent materials.

The chief object of my invention is to provide a method of manufacturing decorative sheets suitable for use as floor or wall coverings. An object of my invention is to provide a method of manufacturing decorative sheets which is more economical than the processes heretofore in use and which produces a highly desirable variegated surface effect. A further object is to provide a method adapted to produce substantially the same variegated, grained, or marble appearance, and color value in linoleum sheets so that a sheet made at one time from given materials can be used successfully with a sheet made at another time from similar materials. A still further object is to eliminate, in the manufacture of continuous decorative sheets, any visible joint or discontinuity usually discernible when a number of separate, independent sheets are united to form a single, continuous sheet.

I will describe my invention with particular reference to the manufacture of linoleum having a variegated surface effect. In my process, a blend or "mix" of differently colored granular compositions is formed into a cohesive sheet having a predetermined direction of graining, ribs or grooves being formed in the sheet after its formation or during its formation, such ribs or grooves, preferably, extending in the same direction as the direction of graining. A grooved sheet so formed is severed into sections, the sections then being overlapped to some extent, and thereafter subjected to pressure applied in a direction normal to the direction of graining. Such pressure removes the grooves in the overlapped sections and forms a continuous sheet having a plane surface. By subjecting the ribbed, grained sections to such pressure, the graining effect is shortened and spread in a direction normal to the direction of graining thus presenting a variegated surface effect in which individual colors appear without substantial blending or smearing. It will be appreciated, heretofore, a visible joint or discontinuity, commonly denoted in the industry as a "hook-on," was discernible after the formation of the continuous sheet. Such discontinuity is obviated in the variegation of the continuous sheet by the

rib formation of the overlapped sheets in accordance with my invention. The sheet may then be employed with other sheets of plain or variegated color in the formation of block inlaid linoleum by means of the well-known automatic inlaying machines of the Walton or Batten type. Usually, however, it will be applied in continuous lengths to a suitable backing, such as burlap, saturated felt or the like.

10 The general trend of the pattern is determined by the make-up of the granular compositions from which the sheet is formed. Differently colored compositions are used, any number of colors being used as desired. Once the make-up of a 15 mix is determined, comparable effects can be produced at will simply by reproducing the mix and subjecting it to my process.

15 The accompanying drawing illustrates a preferred manner of carrying out my invention, in which

20 Figure 1 is a diagrammatic view illustrating the preferred method of carrying out my invention; and

25 Figure 2 is an isometric view, exaggerated in size, of overlapped sheets serving to illustrate the manner in which visible joints are eliminated in the formation of a continuous sheet.

30 Suitable mixing equipment is provided for forming two differently colored linoleum compositions. It will be appreciated suitable equipment may be provided for any required number of differently colored compositions. As shown in Figure 1, the differently colored compositions are blended into a cohesive vari-colored mass which 35 is fed to a two-roll calender, the roll 4 of such calender having a smooth, plane surface while the roll 5 thereof is ribbed or grooved, thus forming the mass into a non-planar sheet 6 provided with grooves or depressed portions 7 and 40 standing portions or ribs 7a. The roll 5, of course, may be provided with any desired forms or shapes of ribs or grooves. In the calender, preferably, the face roll, roll 5 as illustrated in Figure 1, is maintained at a lower temperature 45 than the back roll. The roll 5 is rotated at the same or a slightly greater speed than the roll 4 which extrudes the granules and permits a "wiping" action spreading the differently colored granules to some extent, thus forming what is 50 known in the industry as a "jaspe" sheet. It will be appreciated the ribbed roll 5 forms grooves 7 and ribs 7a in the sheet 6 extending longitudinally thereof in the same direction as the graining without disturbing or interfering in any way with the formation of such graining.

Preferably, such ribs and grooves are formed in the face of the sheet, although they may be formed in its back, if desired.

The sheet 6 is then severed by any suitable device or manually in sections 8. The sections 8 are then turned at right angles to the direction of graining and cross-rolled. In other words, the sections 8 are calendered or compacted by being passed through a two-roll calender similar to the calender above described except that both rolls thereof have smooth surfaces. By careful control of the roll temperatures, variegated effects can be obtained regardless whether the grooves and ribs were formed in the face or in the back of the sheet.

The step of cross-rolling removes the grooves and ribs in the sections 8 and shortens and spreads the directional graining thereby presenting a variegated surface in which individual colors appear without substantial blending or smearing. Preferably, the sections 8 are overlapped as shown at 9 before the step of cross-rolling in order that a continuous sheet 10 may be formed by the cross-rolling operation. The ribbed formation of the overlapped sheets obviates any visible discontinuity where the sheets are joined to form the continuous sheet. The sheet 10 so formed may then be applied in continuous lengths to a suitable backing, such as burlap, saturated felt or the like, or may be employed with other sheets of plain or variegated colors in the formation of block inlaid linoleum.

In Figure 2, I have illustrated a modification of the rib formation which likewise serves to obviate any visible discontinuity in a continuous sheet caused by the overlapping of separate individual sheets. In the formation of the individual sections 8, a depressed portion 7 is provided adjacent the edge of the section 8 designed to overlap a second similar section in the formation of a continuous sheet. Such depressed portion 7, of course, may be formed as above described. Preferably, the depressed portion 7 overlies or is adjacent to a similar depressed portion 7 in the overlapped sections. Thus, it will be observed the thickness of the overlapped sheets at the juncture between sheets is considerably less than the thickness of the overlapped portions of such sheets so that any visible discontinuity or joint between the sheets is eliminated when the sheets are compacted or calendered to form a continuous sheet.

While I have described a method of eliminating a visible joint or discontinuity in a continuous sheet caused by the juncture between overlapped sheets in conjunction with a particular variegated surface effect, it will be understood my invention is not limited to such use, since visible joints caused by overlapping individual sheets in the formation of a single continuous sheet of any desired surface appearance may be substantially eliminated by forming a depressed portion adjacent the edge of the overlapped sheet thus reducing the thickness of the overlapped sheets at their juncture.

While I have described the sections 8 as being turned at right angles to the direction of graining before the cross-rolling operation, it will be understood such sections may be calendered in the direction of the grooves, if desired, since such calendering permits a variegated surface effect to be obtained, although such effect is not so satisfactory as the effect obtained by cross-rolling.

In a modification of my preferred process, vari-colored granular compositions may be

formed in a "jaspe" sheet, then providing such sheet with grooves and ribs by passing it through a calender having a ribbed roll or any other means suitable for forming ribs and grooves in the sheet, and following the remaining steps of the method above described.

If desired, a series of knives may be placed adjacent the two-roll calender which forms the sheet 6 to cut grooves in such sheet, thus permitting 10 the formation of a ribbed sheet as described above. It should be understood, however, if this process be followed, a slightly different variegated effect is obtained since the graining on the jaspe sheet varies to some extent throughout the 15 thickness of such sheet.

It will be appreciated the essential features of my invention reside in the formation of a ribbed jaspe sheet and compacting or calendering such sheet to remove the ribs and render the surface 20 of the sheet planar in form, thereby shortening and spreading the jaspe graining thus providing a variegated surface effect in which the individual colors appear or stand out without substantial blending or smearing, and in the elimination of 25 visible joints or discontinuities where overlapped sheets or sections are joined to form a continuous sheet.

While I have described my invention with particular reference to the manufacture of a variegated linoleum sheet, it will be understood my invention may be used in the manufacture of rubber, asphalt or similar types of floor or wall covering to produce the desired variegated surface effect.

The advantages of my invention are readily perceived. An entirely new and different type of surface ornamentation is provided at less cost than other types of surface ornamentation since my method provides various manufacturing advantages over processes heretofore in general use. Higher temperatures may be used at the rolls of the sheeting calenders than has heretofore been customary in the industry thus effecting a saving in refrigerating costs; chill marks frequently caused by extremely low temperatures at the rolls of the sheeting calender are eliminated; and the cement content of the mix may be reduced since higher roll temperatures are permitted, thus effecting a saving in maturing time of the finished sheet.

While I have described and illustrated preferred forms of my invention, it will be understood my invention is not so limited but may be otherwise embodied and practiced within the 55 scope of the following claims.

I claim:

1. In the method of manufacturing a decorative sheet, the steps comprising, blending differentially colored granular compositions to form a cohesive vari-colored mass, forming said mass in a sheet having a definite directional graining, depressing portions of said sheet below the plane surface thereof, severing said sheet in sections, and calendering said sections at an angle to the direction of graining, thereby shortening and spreading the directional graining and presenting a variegated surface effect in which individual colors appear.

2. In the method of manufacturing a decorative sheet, the steps comprising, blending differentially colored granular compositions to form a cohesive vari-colored mass, calendering said mass in a sheet having a definite directional graining and having a plurality of grooves in a surface thereof, and calendering said sheet in a direction

normal to the direction of graining thereby shortening and spreading the directional graining and presenting a variegated surface effect in which individual colors appear.

3. In the method of manufacturing a decorative sheet, the steps comprising, blending differently colored granular compositions to form a cohesive vari-colored mass, calendering said mass in a sheet having a definite directional graining and having a plurality of grooves in a surface thereof, the grooves in said sheet extending in the same direction as the graining, severing said sheet in sections, turning said sheets at an angle to the direction of graining, and calendering said sections thereby shortening and spreading the directional graining and presenting a variegated surface effect in which individual colors appear.

4. In the method of manufacturing a continuous sheet from separate individual sheets without substantial visible discontinuity where the sheets are joined to form a continuous sheet, the steps comprising, forming a depressed portion adjacent the edge of a sheet, overlapping similar sheets, the overlapped thickness of said sheets being greater than the thickness at the juncture thereof, and compacting said sheets to form a continuous sheet.

5. In the method of manufacturing a continuous sheet from separate individual sheets without substantial visible discontinuity where the sheets are joined to form a continuous sheet, the steps comprising, forming a depressed portion adjacent the edge of a sheet, forming a depressed

portion in a second sheet, overlapping said sheets so that the depressed portion adjacent the edge of said sheet lies adjacent the depressed portion in said second sheet, and compacting said sheets to form a continuous sheet.

6. In the method of making linoleum having a variegated surface effect, the steps comprising, blending differently colored granular compositions to form a cohesive vari-colored mix, forming said mix in a sheet having a definite directional graining and having a plurality of grooves in a surface thereof, the grooves in said sheet extending in the same direction as the graining, and subjecting said sheet to pressure to remove said grooves thereby shortening and spreading the directional graining and presenting a variegated surface effect in which individual colors appear.

7. In the method of making a decorative sheet, 20 the steps comprising, forming a vari-colored mass of differently colored granular compositions, subjecting said mass to pressure to form a sheet having a definite directional graining, forming a plurality of grooves in said sheet without substantially disturbing the directional graining, said grooves extending in the same direction as the graining, severing said sheet in sections, overlapping said sections, and thereafter subjecting said overlapped sections to cross-rolling to remove said grooves and to shorten and spread the directional graining.
